UNITED STATES PATENT OFFICE.

ERVIN E. STRAWN, OF DES MOINES, IOWA, ASSIGNOR TO THE OMNIGRAPH COMPANY,
OF DES MOINES, IOWA, A CORPORATION.

ADDRESS-PRINTING MACHINE.

1,414,103.

Specification of Letters Patent. Patented Apr. 25, 1922.

Application filed January 13, 1921. Serial No. 436,914.

To all whom it may concern:

Be it known that I, ERVIN E. STRAWN, a citizen of the United States, and a resident of Des Moines, in the county of Polk 5 and State of Iowa, have invented a certain new and useful Address-Printing Machine, of which the following is a specification.

The object of my invention is to provide an address printing machine, which may be 10 used in connection with a newspaper printing press or otherwise for printing different addresses on paper.

A further object is to provide such a machine, which may be employed for printing 15 addresses on a moving web of paper at a high rate of speed.

A further object is to provide such an address printing machine, having means for successively bringing address plates to printing 20 positions and printing from them, said means including a member traveling in a rotary path, and means for causing the address plate to travel at the same rate of speed as the paper during the printing operation and for causing said member to travel 25 at a different rate of speed during part of its movement for the purpose of printing on the paper at relative distances, differing from the length of the path of travel of 30 the address plate on said member.

A further object is to provide in such a machine, means for mounting the additional printing mechanism for permitting its adjustment laterally for printing at different 35 positions on the web of paper.

An additional object is to provide such a machine adapted to be used in combination with a printing press and to provide special means for connecting the machine with the 40 printing press.

Still a further object is to provide such an address machine, and means for mounting it on a printing press, and means for automatically throwing the address printing 45 mechanism out of gear, when the web of paper is broken in its passage through the printing press.

Still a further object is to provide in such an address printing machine, peculiar means 50 for moving the address plates to printing position and to provide means for taking the address plates from said last means by positively acting devices.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a side elevation of my improved address printing machine mounted on the frame of a printing press.

Figure 2 shows a top or plan view of a 65 portion of the address printing machine.

Figure 3 shows a detailed, sectional view taken on the line 3—3 of Figure 5 of a part of the address printing device.

Figure 4 shows a horizontal, detailed, sectional view of part of the gearing for operating the address printing machine.

Figure 5 shows a detailed end view of the address printing machine, parts being broken away.

Figure 6 shows a vertical, sectional view through the address printing machine.

Figure 7 shows a detailed, sectional view taken on the line 7—7 of Figure 6.

Figure 8 shows a detailed, sectional view 80 taken on the line 8—8 of Figure 6.

Figure 9 shows a plan view of the rotary plate carrying member and magnet.

Figure 10 shows an end elevation of part of the same.

Figure 11 shows an enlarged, detailed, sectional view of the impression roller and the plate guide adjacent thereto.

Figure 12 shows a side elevation of a part of the address printing mechanism, showing 90 part of the means for automatically rendering the mechanism inoperative under certain circumstances of the operation of the press with which said mechanism is used.

Figure 13 is a transverse, detailed, sectional view taken on the line 13—13 of Figure 6.

Figure 14 shows a perspective view of one of the address plates; and

Figure 15 shows a detailed view of a modified form of circuit maker.

My improved address printing machine may be used with a printing press or independently, but is illustrated herein in a form 105 peculiarly adapted for use with a printing press for the printing of newspapers or the

like from the web of paper drawn from a roller.

In the accompanying drawings, I have used the reference numeral 10 to indicate generally the frame of a certain type of newspaper printing press now commonly used. At 11, I have shown part of the operative gearing mechanism of the printing press.

10 In the ordinary use of the press, where my address printing mechanism is not used, the web of paper 12 is drawn through the press from the point A to the point B. Where my improved address printing device 15 is used in connection with the printing press, a supporting frame, such for instance, as the frame 13, is employed, and mounted on the main printing press frame.

20 The frame 13 really comprises two laterally spaced frames, which are connected near their upper ends by a pair of horizontal fore-and-aft spaced shafts 14 and 15.

25 In Figure 6, I have shown a slightly modified form of the device, in which the members of the frame 13 are connected by cross bars 16.

I have shown in the drawings two methods for mounting the address printing mechanism proper on the frame 13. In Figures 1, 30 2, 3, and 5, I have shown the address printing machine proper slidably mounted on the shafts 14 and 15. In Figure 6, I have shown the address printing mechanism provided with the frame members 17 received in suitable 35 grooves in the cross bars 16. The address printing mechanism is supported on a frame 18, comprising spaced side members, as shown in Figures 1, 5 and 7 for instance, slidably mounted on the frame 13 in either 40 of the manners hereinbefore described.

45 Mounted in the frame members 18 is a transverse shaft 19. Spaced below the shaft 19 is the shaft 20, on which is the impression roller 21. The impression roller 21 is considerably longer than the shaft 19, so that the frame members 18 may be slid laterally without effecting the impression roller 21.

The shaft 20 is mounted in the frame members 13.

50 Mounted on the side of the frame 10 is an upright shaft 22 on which is a gear 23, which meshes with the gear 11. At the upper end of the shaft 22 is a gear 24, which meshes at right angles with the gear 25 on the impression roller shaft 20.

The gear 25 meshes with an idler gear 26 mounted on the frame 13. Mounted on the frame 13 is a transverse shaft 27 on which is a gear 28 in mesh with the gear 26.

60 On the shaft 27 is slidably but non-rotatably mounted a gear 29, shown for instance in Figure 5.

65 On one of the frame members 18 is mounted a bracket 30, having arms 31 arranged on opposite sides of the gear 29, for thereby

causing the gear 29 to slide laterally in the machine when the frame members 18 are moving laterally in the machine.

On one of the frame members 18 at the opposite side of the address printing mechanism from the gear 28 is a short shaft 32 on which is mounted a gear 33 arranged in mesh with the gear 29.

70 Mounted in the frame members 18 is the shaft 19, already mentioned. Fixed to the shafts 32 and 19 and arranged in mesh with each other are elliptical gears 35 and 36 shown in Figure 3.

75 Mounted at the top of the frame members 18 is a magazine 37, which is substantially channel-shaped, having the back member 38, the side members 39 and the front flanges 40.

80 In my improved address printing machine, I provide means for carrying address plates received in the magazine 37 from said magazine, past inking devices to position for printing in cooperation with the impression roller 21. I will now describe the mechanism for accomplishing this operation.

85 Mounted on the frame members 18 just below the magazine 37 are guide and supporting members 41, one of which is clearly illustrated in Figure 6, and both of which are shown in Figure 7, having their upper 90 surfaces curved on the arc of a circle, having its center at the center of the shaft 19. The shaft 19 is the main operating shaft for the address plate mechanism.

95 On the shaft 19 between the frame members 18 and below the magazine 37 is a member, which I shall call the rotary plate carrying member, comprising a body 42 elongated in both directions from the shaft. Secured to the plate carrying member 42 on opposite 100 sides thereof are permanent horse shoe magnets 43 and 44. The ends of the arms of the magnets 43 and 44 project to positions substantially flush with the ends of the member 42, as illustrated for instance in Figure 9.

105 Between the arms of the magnets at the opposite ends of the plate carrying members 42 and on opposite sides thereof are lugs 45. The magnets at their closed ends terminate short of the adjacent ends of the body 42, 110 as illustrated in Figures 6 and 9 and 10.

115 Secured to the plate carrying member 42 at each end thereof is a pair of small plates 46, which project radially slightly beyond the ends of the member 42, as shown for instance in Figures 6 and 9. These plates 46 have their outer surfaces curved in the circle of the path in which they travel.

120 The plates 46 have shoulders for engaging the lowermost address plate in the magazine 37 for removing it from said magazine during the rotation of the member 42.

125 Pivoted adjacent to the inner surfaces of the frame members 18 by means of the shafts 47 are plates 48, which project forwardly in 130

the machine beneath the magazine 37 at opposite sides thereof.

Formed in the inner surface of each plate 48 is a curved guide groove 49, such as that shown in Figures 6 and 7. The material near the rearward end of the groove 49 and below said groove is cut away, as shown at 50 in Figure 6, so that the rib 51 below the guide groove 49 is tapered at its rear end.

10 The plates 48 are normally held in their positions, as illustrated in Figure 6, by means, which will hereinafter be more fully referred to.

On the member 42 are lugs 52, as shown 15 by dotted lines in Figure 6 and by full lines in Figure 10, which travel through the grooves 49 when the plates 48 are in their normal positions, as shown for instance in Figures 6 and 7.

20 Means which will be hereinafter more fully referred to, are provided for tilting the plates 48 upwardly thereby raising the address plates in the magazine 37, and thereby preventing the removal of any plate from 25 such magazine by the rotating member 42. This raising movement of the plates 48 occurs when the web of paper is broken in the manner hereinafter more fully described, so that when the paper web is broken, the 30 address plate handling mechanism will cease to be operated, until the web of paper travels properly through the machine again.

It will be seen that when the plate carrying body 42 is rotated for carrying one end 35 of said body beneath the magazine 37, the plates 46 will engage the edge of the lowermost address plate in said magazine and carry such address plate away from the lower part of the magazine.

40 The member 42 rotates in the direction indicated by the arrow in Figure 6.

The address plate carried from the magazine by engagement with the plates 46 slides on the guide 42 for a short distance. Overlapping the end of the guide 42, as shown 45 in Figure 6, is an outer guide 53, which extends more than half way around the path of travel of the address plates, as illustrated for instance in Figure 6.

50 It will be seen that the address plate will be slid around its path, and that its ends will be prevented from moving radially outwardly by means of the guides 53, while it can not move inwardly on account of engagement with the end of the plate carrying member 42.

In Figure 6, I have shown a series of inking rollers 54, 55, and 56, from which the address plates are inked during their travel 60 from the magazine 37 to the impression roller 21.

It may be mentioned that the address plates are formed with raised letters and that the guide 53 is very thin in its lower 65 portion, so that even when the ends of the

address plate 57 are resting on the lower part of the guide 53, the raised letters 58 will project downwardly far enough to contact with the impression roller for making a printed impression on the paper. 70

Just below the rear part of the magazine 37 is arranged a transverse shaft 59 mounted in the walls 39 of the magazine 37. The back wall 38 of said magazine terminates above the lower ends of the side walls 39, 75 as illustrated in Figures 6 and 8, and it may be mentioned that the shaft 59 is located below the back wall 38.

On the shaft 59, I mount a pair of fingers 60. A spring 61 is mounted on the shaft 59 80 adjacent to each finger 60 and has one end in engagement with the wall member 38, as at 62, and the other end in engagement with a lug or pin 63 on the adjacent finger 60, so that the finger 60 normally hangs downwardly from the shaft 59 and so that yielding pressure is needed to force the fingers 60 rearwardly. 85

It will be seen that when a plate 57 is slid out of the lower end of the magazine 90 37, it will engage the fingers 60 and force them rearwardly against the pressure of the springs 61.

If on account of frictional engagement between the address plates, the next address 95 plate above the bottom one should tend to slide out, it will be engaged by the fingers 60 and pushed back into position.

For removing the plates from between the ends of the plate carrying member 42 and 100 the guides 53, I have provided the following means:

Suitably mounted between the frame members 18 is a shaft 64. On the shaft 19 is a gear 65 meshing with an idler gear 66. 105 The gear 66 meshes with another idler gear 67, and the gear 66 and gear 67 meshes with the gears 68 on the shaft 64.

On the shaft 64 is a sleeve 69, shown for instance in Figure 13, having at its ends 110 the annular flanges or discs 70. The flanges or discs 70 have in their peripheries at points, which register with each other across the device, recesses 71 shown in Figures 6 and 13, for receiving the ends of an address 115 plate.

Secured to the frame members 18 above the discs 70 and extending from the rear portions thereof over the tops of said discs and then downwardly in front of said discs 120 to positions spaced from and overlapping the respective guides 53, as shown in Figure 6, are plate guides 72.

The address plates 57 are curved from side edge to side edge on the arc of a circle, having its center at the center of the shaft 19 and its periphery in the plate 57 when arranged against the end of the member 42. 125

Extending rearwardly from the members 18 are the sides of a receiving magazine 73. 130

On the inner surfaces of the sides 73 are strips 74, having inwardly inclined projections 75, as shown in Figure 6. The side members 73 are connected by a cross member 76 and by cross rods 77 and 78, as shown in Figure 6.

Extending downwardly from the cross member 76 are the brackets 79 pivoted to the lower ends of which are arms 80 which 10 extend upwardly between the discs 70, as shown for instance in Figures 6 and 13. At the upper end of each arm 80 is a packer finger 81 carrying a roller 82, adapted to coact with a cam 83 on the shaft 64. Springs 15 84 yieldingly hold the rollers 82 in engagement with the cams 83.

The cross member 76 and the rods 77 and 20 78 are provided with slots 85, as shown in Figure 13, to receive selector strips 86 adapted to coact with the address plates 57.

Referring to the automatic cut-out device for rendering the address printing mechanism inoperative when the paper is broken, attention is called to the plates 48, which 25 have already been mentioned. On the shaft 47 at one end thereof outside the frame members 18 is an arm 87 (Fig. 12). Mounted on the frame member 18 adjacent to the arm 87 is a solenoid magnet 88, the armature of which has a stem 89 pivoted to the arm 87, as shown in Figure 12. The one end of the arm 87 is bevelled, as at 90, and arranged adjacent thereto is a hook 91 yieldingly held by a spring 92 in position to be 30 in the path of the bevelled end 90, when the armature is pulled inwardly by the energizing of the solenoid.

The wires 93 and 94 of the solenoid 88 are connected respectively with a plate 95 40 and a swinging roller 96, and are included in a circuit, which has the source of power 97. The spring 98 tends to move the roller 96 toward engagement with the plate 95.

The paper 12 travels adjacent to the plate 45 95 and separates the roller 96 and the plate 95 during the ordinary operation of the machine. When, however, the paper breaks and ceases to travel over the plate 95, then the roller 96 contacts with the plate 95, 50 whereupon the solenoid is energized and the armature moves inwardly for pulling the arm 87 to position where its end will be engaged by the hook 91.

This movement rotates the shaft 47 for 55 swinging the plates 48 upwardly a sufficient distance, so that the members 52 in their travel engage the under side of the rib 51, instead of traveling in the groove 49. When this occurs, the members 52 raise the stack 60 of plates high enough, so that the lower address plate clears the plates 46 at the ends of the plate carrying member 42. When the paper is once more threaded through the machine, the operator releases the hook 91.

65 I will now describe the practical opera-

tion of my improved address printing machine, particularly with reference to its use in connection with a printing press. It may be mentioned that my device may be used in a great variety of ways; the use herein more 70 particularly referred to and explained is simply illustrative.

It may be mentioned that the address plate carrying member 42 is preferably built, so that its plate carrying surfaces travel a path 75 twenty-two inches in circumference when round gears instead of the elliptical gears are used. An address will be printed on each eleven inches length of paper, thus printing two addresses for each rotation of 80 the member 42. The machine is thus built for use with ordinary letter-sized sheets.

Where the device is used for printing on newspapers, which are ordinarily forty-eight inches long, the plates 46 at one end of the 85 address plate carrying member are preferably removed and the elliptical gears are used, whereby for each revolution of the plate carrying member 42, the address plate travels at the same speed as the paper during the printing operation and at a slower speed at other times. If ordinary round gears were used instead of the elliptical gears, one address plate would be printed 90 every twenty-two inches on the paper. 95

It may be mentioned that the address plates are given the proper curvature for use on such a device, which carries them in a circle of twenty-two inches in circumference, and that the various parts are curved to 100 properly accomplish the purpose.

Assuming that the paper from which the newspaper is to be printed is properly threaded through the machine and is extended from the point A round the guide 105 99 and thence around the impression roller 21 and thence around the guide 100, and that a proper stack of address plates has been arranged face up in the magazine 37, it will be seen that when the press is run, rotation 110 will be imparted through the gears 11 and 23, the shaft 22 and the gear 24 to the gear 25, the shaft 20 and the impression roller.

Rotation will be imparted from the gear 25 through the gear 26 to the gear 28 and the 115 shaft 27. The shaft 27 rotates the gear 29, which in turn rotates the gear 33 and the shaft 32.

The elliptical gear on the shaft 32 rotates the elliptical gear 36 on the shaft 19. The 120 shaft 19 is thereby rotated for rotating the address plate carrying member 42.

As the address plate carrying member moves from its position shown in Figure 6 anti-clockwise, the members 52 travel 125 through the grooves 49 and the plates 48 are not in anyway effected.

The plate carrying member 42 is of such length that the plates 46 are located between the frame members 18 and the plates 130

48 and readily clear the plates 48 in the rotation of the member 42.

The plates 46 engage the edge of the lowermost address plate 57, forcing it out of the magazine 37. The movement of the plate 57 swings the fingers 60 against the tension of the springs 61. Ordinarily the second plate 57 will not be moved, but if it should be moved slightly, then as soon as 10 the fingers 60 clear the lowermost plate 57, they will move the next plate back to its position in the magazine.

The lowermost plate 57 slides on the guide 41 and then is moved along between the 15 guide 53 and the plate carrying member 42. The use of the magnets is two-fold.

The speed of the machine is such that gravity might not feed the plates downwardly fast enough in the magazine, and the use 20 of the magnets tends to cause the lowermost plate to drop downwardly properly. The use of the magnet also prevents the plate from sliding on the end of the member 42 during the downward part of its travel.

25 The plate is carried past the inking rollers and then inked, and then to the printing position, where the impression is made on the paper traveling over the printing roller.

The paper travels, of course, at a substantially uniform rate of speed, and the parts are so geared that the address plate travels at the same speed as the paper during the printing operation. The member 42 travels at a slower rate of speed during other parts 35 of its rotary movement.

The plate carrying member 42 is of such size that the address printing mechanism may be used for printing on a strip of paper at eleven inch distances; that is to say for 40 printing on ordinary letter sheets by simply taking off the elliptical gears and mounting proper sized gears in their place.

Where the device is used for printing a newspaper, the address plates are made more 45 than eleven inches apart, and hence the plates 46 on one end of the plate carrying member 42 are removed and the elliptical gears are used for slowing down the speed of the address plate carrying member during the printing operation.

50 After the printing operation, the plates 46 carry the address plate along the guides 53 until the address plate passes between the guides 53 and the guide 72 and at the proper time reaches the notches 71.

It will, of course, be understood that the discs 70 are so timed in their rotation, as to bring the notches 71 to position to receive the address plate at the proper time. The 60 guide 72 is so shaped so as to force the address plate into the notches 71, and the further rotation of the discs 70 carries the address plate away from the member 42 to the opposite side of the shaft 64.

65 As the address plate, received in the

notches 71, travels downwardly near the receiving end of the magazine 73, the roller 82 reaches the lower part of the cam 83, and the packer finger 81 is drawn toward the shaft 19, as shown in Figure 6, by means of the 70 spring 84.

At the proper time, the high part of the cam 73 engages the roller 82, whereupon the packer finger 81 is moved toward the magazine 73 for pushing the address plate out 75 of the notches 71 and into the magazine and past the first spring engaging members 75.

It will be seen that the mounting of the cam 83 on the shaft 64, which supports the discs 70, insures the positive synchronous 80 operation of the cam and discs. The use of the cam gives the packer fingers 81 a steady pushing movement.

It will, of course, be understood that the address printing mechanism may easily be 85 thrown out of gear manually at any time. If the paper is broken and fails to travel between the plate 95 and the roller 96, then the roller 96 will contact with the plate 95 for energizing the solenoid 88, and thereby 90 rocking the shaft 47 for raising the plates 48 slightly.

When the plates 48 are thus raised, the lugs 52 travel below the ribs 51 for raising the plates 48 and lifting the pile of address 95 plates and preventing the fingers 46 from engaging one of said address plates. The arm 87 will be engaged by the hook 91 for holding the plates 48 in position for holding up the pile of address plates. The address 100 printing mechanism is thus rendered inoperative. The hook 91 may be released, when desired. However, the plates 48 will not drop to their normal position until the lugs 52 clear said plates and thus there can be no 105 injury to the machine when the hook 91 is released.

Attention is called to the fact that the address printing device is rendered inoperative without throwing it out of gear. Hence, after 110 the paper has been broken, and is again threaded through the machine, then when the hook 91 is released, it follows that because the press and addressing printing mechanism are geared together, the addresses will be printed at the proper place on the newspaper. The plate carrying member 42 is never thrown out of gear with relation to the printing rollers of the press, and when the hook 91 is released, and the 120 member 42 begins to operate on the address plates again, the addresses will be printed at the proper place.

In Figure 15, I have shown a slightly modified form of the circuit making device, 125 in which the wire 94 is connected with a plate 95^a, and the wire 93 is connected with a swinging lever 95^c, which carries the roller 96^a.

65 The paper 12 in its ordinary travel holds 130

the roller 96^a in raised position, so that the lever 95^c is free from contact with the plate 95^a. When the paper breaks or sags, the lever 95^c contacts with the plate 95^a for energizing the solenoid 88.

Attention is called to the fact that the machine involved in the present application has been particularly designed for printing addresses on a continually moving strip of 10 paper at eleven inch intervals. For accomplishing this purpose, the plate carrying member is so made, that its plate carrying surfaces travel in a path twenty-two inches in circumference. By printing from plates 15 on both ends of the carrying member, addresses may be printed at regular eleven inch intervals. The plates are curved to conform to the curvature of such path. It is desirable to make the machine for printing 20 on letter-sized sheets, so that the addresses may be used in printing upon letters and the like.

In the present instance, I have adapted such a machine for use with a newspaper printing press and have thus made a machine, which can be readily used for a 25 variety of purposes. Newspapers are ordinarily forty-eight inches long and it has become necessary to so modify the machine, 30 as to cause the addresses to be printed at forty-eight inch intervals. This is accomplished by printing from one end only of the plate carrying member and by using the elliptical gears, which make it possible 35 to carry the plates at the same speed as the paper during the printing operation and to slow down the speed of the plate carrying member during the other portion of its movement, so that the address plates are 40 thus presented to printing position at forty-eight inch intervals on the paper.

Particular attention is called to the great accuracy and certainty of operation of my machine, which is not only desirable in the 45 use of such a machine in connection with a printing press for newspapers, but also in connection with the printing of form letters. Attention is also called to the fact that such a machine, as is here involved, can be operated 50 at a sufficient speed for printing on newspapers.

Ordinary address printing machines do not have the necessary speed, such speed is secured in the present case by the general 55 construction of the machine and by the use of rotary members at all points, where the address plates are handled.

I claim as my invention:

1. In an address printing machine, a 60 frame, an address plate magazine, a rotary address plate carrying member mounted on said frame, means on said member for engaging one plate in said magazine for removing it therefrom, guides below said 65 magazine, on which said plates may travel,

guides on said frame for holding a plate between the guides and the plate carrying member, a discharging guide member adapted to move a plate away from said plate carrying member, as said plate is advanced 70 along said last guides, a rotary member having means for receiving the plate when thus moved from said plate carrying member.

2. In an address printing machine, a frame, an address plate magazine, a rotary 75 address plate carrying member mounted on said frame, means on said member for engaging one plate in said magazine for removing it therefrom, guides below said magazine on which said plates may travel, 80 guides on said frame for holding a plate between the guides and the plate carrying member, a discharging guide member adapted to move a plate away from said plate carrying member, as said plate is advanced 85 along said last guides, a rotary member having means for receiving the plate when thus moved from said plate carrying member, said plate carrying member having a permanent magnet thereon. 90

3. In an address printing machine, a frame, an address plate magazine, a rotary address plate carrying member mounted on said frame, means on said member for engaging one plate in said magazine for removing it therefrom, guides on said frame for holding a plate between the guides and the plate carrying member, a discharging guide member adapted to move a plate away from said plate carrying member, as said plate is advanced along said last guides, a rotary member having means for receiving the plate when thus moved from said plate carrying member. 95

4. In an address printing machine, a 105 frame, an address plate magazine, a rotary address plate carrying member, means on said frame and said plate for engaging and guiding an address plate in a rotary path, and a guide element and a rotating mechanical device for taking said plate from said 110 plate carrying member.

5. In an address printing machine, a frame, an address plate magazine, a rotary address plate carrying member, coacting 115 means on said frame and said plate carrying member for engaging and guiding an address plate in a rotary path and prevent its radial movement and a rotating mechanical device for taking said plate from said 120 plate carrying member.

6. In an address printing machine, a frame, an address plate magazine, a rotary address plate carrying member mounted on said frame, means on said member for engaging one plate in said magazine for removing it therefrom, guides below said magazine, on which the plates in said magazine may rest and on which said plates may travel, guides on said frame for holding a 130

plate between the guides and the plate carrying member, a discharging guide member adapted to move a plate away from said plate carrying member, as said plate is advanced along said last guides, a rotary member having means for receiving the plate when thus moved from said plate carrying member.

7. In an address printing machine, a frame, an address plate magazine, a rotary address plate carrying member mounted on said frame, having a curved surface, means on said member for engaging an address plate, a curved address plate adapted to rest on said surface, guides on said frame for coacting with said member in the movement of the address plate in a rotary path, a rotary discharging device having a recess reversely curved, as shown with relation to 15 said surface, and means for moving said address plate from said member into said recess.

8. In an address printing machine, a frame, an address plate magazine, a rotary address plate carrying member mounted on said frame, having a curved surface, means on said member for engaging an address plate, a curved address plate adapted to rest on said surface, guides on said frame for co- 20 acting with said member in the movement of the address plate in a rotary path, a rotary discharging device having a recess reversely curved, as shown with relation to 25 said surface, means for moving said address plate from said member into said recess, and means for removing said plate from said recess.

9. In an address printing machine, a frame, an address plate magazine, a rotary address plate carrying member mounted on said frame, having a curved surface, means on said member for engaging an address plate, a curved address plate adapted to rest on said surface, guides on said frame for co- 30 acting with said member in the movement of the address plate in a rotary path, a rotary discharging device having a recess reversely curved, as shown with relation to 35 said surface, means for moving said address plate from said member into said recess, and means for removing said plate from said recess.

40 10. In an address printing machine, a frame, an address plate magazine, a rotary address plate carrying member mounted on said frame, having a curved surface, means on said member for engaging an address plate, a curved address plate adapted to rest on said surface, guides on said frame for co- 45 acting with said member in the movement of the address plate in a rotary path, a rotary discharging device having a recess reversely curved, as shown with relation to 50 said surface, means for moving said address plate from said member into said recess, and means for preventing the movement of said plate from said recess during part of the rotation of said discharging device, and means for removing the plate from said recess. a packer finger, a cam for operating said finger and a common shaft for said discharge device and said cam.

reversely curved, as shown with relation to said surface, and means for moving said address plate from said member into said recess, the curvature of said plate and said surface and said recess being substantially 70 the same.

11. In an address printing machine, a frame, an address plate magazine, a rotary address plate carrying member mounted on said frame, having a curved surface, means 75 on said member for engaging an address plate, a curved address plate adapted to rest on said surface, guides on said frame for coacting with said member in the movement of the address plate in a rotary path, a rotary discharging device having a recess reversely curved, as shown with relation to 80 said surface, means for moving said address plate from said member into said recess, means for preventing the movement of said 85 plate from said recess during part of the rotation of said discharging device, and means for removing the plate from said recess, said means including a cam actuated packer finger.

90 12. In an address printing machine, a frame, an address plate magazine, a rotary address plate carrying member mounted on said frame, having a curved surface, means 95 on said member for engaging an address plate, a curved address plate adapted to rest on said surface, guides on said frame for coacting with said member in the movement of the address plate in a rotary path, a rotary discharging device having a recess reversely 100 curved, as shown with relation to said surface, means for moving said address plate from said member into said recess, means for preventing the movement of said plate from said recess during part of the rotation 105 of said discharging device, and means for removing the plate from said recess. a packer finger, a cam for operating said finger and a common shaft for said discharge device and said cam.

110 13. In a machine of the class described, a machine through which paper may be advanced, an address printing mechanism, and means for automatically rendering said address printing mechanism inoperative 115 when the paper ceases to advance through the machine.

14. The combination of a printing press and an address printing device having their operative parts operatively connected to 120 together for proper synchronous action, said address printing device having a magazine for address plates, and means for successively taking plates from said magazine and printing from them on paper passing 125 through the press, and means for moving such plates to position where they can not be operated on by said last means.

15. The combination of a printing press and an address printing device having their 130

frame, an address plate magazine, a rotary address plate carrying member mounted on said frame, having a curved surface, means on said member for engaging an address plate, a curved address plate adapted to rest on said surface, guides on said frame for coacting with said member in the movement of the address plate in a rotary path, a rotary discharging device having a recess

operative parts operatively connected together for proper synchronous action, said address printing device having a magazine for address plates and means for successively taking plates from said magazine and printing from them on paper passing through the press, and means for moving such plates to position where they can not be operated on by said last means, when the paper fails to travel through the press.

16. The combination of a printing press and an address printing device having their operative parts operatively connected together for proper synchronous action, said address printing device having a magazine for address plates, and means for successively taking plates from said magazine and printing from them on paper passing through the press, and means for moving such plates to position where they can not be operated on by said last means, adapted when released to permit the plates to move back to normal position.

17. The combination of a printing press and an address printing device having their operative parts operatively connected together for proper synchronous action, said address printing device having a magazine for address plates and means for successively taking plates from said magazine and printing from them on paper passing through the press, and means for rendering said address printing device inoperative without disconnecting the operative parts thereof with the operative parts of the press.

18. The combination of a printing press with an address printing device, means for gearing said press and said device together for synchronous operation, and means for rendering said address printing device inoperative without disconnecting said gearing means.

19. The combination of a printing press with an address printing device, means for gearing said press and said device together for synchronous operation, and means for rendering said address printing device inoperative without disconnecting said gearing means, when paper ceases to travel through said press.

20. In an address printing mechanism, means for supporting a moving strip of paper, and means for printing addresses thereon, comprising a rotary member, a magazine for address plates, and means adapted to be interposed between said rotary member and said plates for rendering the device inoperative.

21. In an address printing mechanism, means for supporting a moving strip of paper, and means for printing addresses thereon, comprising a rotary member, a magazine for address plates, and means adapted to be interposed between said ro-

70
tary member and said plates for rendering the device inoperative, said means being adapted to be actuated automatically when the paper ceases to travel through the machine.

22. In an address printing mechanism, means for supporting a moving strip of paper, and means for printing addresses thereon, comprising a rotary member, a magazine for address plates, and means 75 adapted to be interposed between said rotary member and said plates for rendering the device inoperative, and means for holding said last means inoperative during the normal travel of the paper through the machine.

23. In an address printing mechanism, a magazine for holding address plates, a rotary plate moving member adapted to successively take one plate at a time from the 85 magazine, and means for raising the plates in the magazines for rendering the moving and plate carrying member inoperative.

24. In an address printing mechanism, a magazine for holding address plates, a rotary plate moving member adapted to successively take one plate at a time from the magazine, and means for raising the plates in the magazines for rendering the moving and plate carrying member inoperative, said 90 means adapted to be actuated when the paper ceases to pass through the machine.

25. In an address printing machine, the combination of a pair of plate carrying members mounted adjacent to each other for rotation in opposite directions, with their peripheries traveling at substantially the same speed, with a frame for guiding a plate from one member to the other, having portions corresponding in curvature to the path of 100 travel of the plate on one of said members and portions corresponding in curvature to the path of travel of such plate on the other of said members.

26. In an address printing machine, the 110 combination of a pair of plate carrying members mounted adjacent to each other for rotation in opposite directions, with a frame and guides on said frame for guiding a plate from one member to the other during the rotation of said members.

27. In an address printing machine, the combination of a pair of plate carrying members mounted adjacent to each other for rotation in opposite directions, with a frame 120 and guides on said frame for guiding a plate from one member to the other during the rotation of said members for moving said plate from the path of rotation of one member to the path of rotation of the other member.

28. In an address printing machine, the combination of a pair of plate carrying members mounted adjacent to each other for rotation in opposite directions, with a frame, and guides on said frame for guiding a plate 130

from one member to the other during the rotation of said members, in a path having portions describing tangential curves.

29. In an address printing machine, the combination of a pair of plate carrying members mounted adjacent to each other for rotation in opposite directions, with a frame and guides on said frame for guiding a plate from one member to the other during the rotation of said members, and means on said members for causing such plate to travel along said guides.

30. In an address printing machine, the combination of a pair of plate carrying members mounted adjacent to each other for rotation in opposite directions, with a frame and guides on said frame for guiding a plate from one member to the other during the rotation of said member, and fixed means on said member for causing such plate to travel along said guides.

31. In an address printing machine, a frame, an address plate magazine, a rotary address plate carrying member, and means for imparting rotation to said member, whereby the member rotates at one speed during a printing operation and at other

speeds during the remainder of the rotation of said member.

32. In an address printing machine, a frame, an address plate magazine, a rotary address plate carrying member, an impression roller, means on said frame for guiding a plate carried by said carrying member in a rotary path to printing position and beyond, and a magnet on said carrying member for holding such a plate against advancing movement with relation to said carrying member.

33. In an address printing machine, a frame, an address plate magazine, a rotary address plate carrying member, an impression roller, a rotary plate receiving member, means on said frame for guiding a plate carried by said carrying member in a curved path from said carrying member to said rotary plate receiving member, a magnet on said carrying member tending to hold an address plate against the plate carrying member during the part of movement of said plate along said guide.

Des Moines, Iowa, December 29, 1920.

ERVIN E. STRAWN.
